UNITED STATES PATENT OFFICE

109,645

DESIGN FOR A CRIB

Susan Clare Pearson, New York, N. Y.

Application February 15, 1938, Serial No. 75,129

Term of patent 14 years

To all whom it may concern:

Be it known that I, Susan Clare Pearson, residing in the Borough of Manhattan, city, county, and State of New York, have invented a new, original, and ornamental Design for a Crib, of which the following is a specification, reference being had to the accompanying drawing, forming part thereof.

In the drawing:

I claim:

The ornamental design for a crib, as shown.
SUSAN C. PEARSON.
